UNITED STATES PATENT OFFICE.

ROBERT N. BAYLIS, OF BLOOMFIELD, NEW JERSEY, ASSIGNOR TO THE BAYLIS COMPANY, OF BLOOMFIELD, NEW JERSEY, A CORPORATION OF NEW JERSEY.

BRUSH-HOLDER RETAINER.

Application filed June 7, 1922. Serial No. 566,672.

To all whom it may concern:

Be it known that I, ROBERT N. BAYLIS, a citizen of the United States of America, residing at Bloomfield, New Jersey, have invented a new and useful Brush-Holder Retainer, of which the following is a specification.

My invention relates to improvements in brush holders and particularly to an improved brush retainer therefor.

In the accompanying drawings—

Fig. 1 is a perspective view of my invention as it appears in use.

Fig. 2 is a perspective view of the retainer slightly modified.

Fig. 3 is a similar view of said device still further modified.

In the drawings, 1 represents the main body of a brush holder which is capable of being mounted on a suitable support 2 adjacent a commutator 3. 4 represents a carbon brush which is supported and guided on the surface 5 of the body of the brush holder 1, which is arranged at an acute angle to the surface of the curve of the commutator. 6 is a spring pressed follower, the end of which bears against the brush 4 so as to feed it toward the commutator 3 and cause it to bear on the latter with the desired degree of pressure. This invention is particularly useful on that type of a holder in which the brush guiding face 5 is arranged at an acute angle to the adjacent surface of the commutator as distinguished from being radial thereto. No claim of novelty is made herein for the brush holder alone. In that type of brush holder shown herein, in which the brush is supported at its rear side only on a surface such as 5, it is desirable to have a retainer which embraces the brush and through which the brush may move. It is also preferable that this retainer shall be made from a strip of metal of uniform width and shall be provided with such fastening means that all of said retainers, irrespective of size, may be interchangeable and secured to the brush holder body without modification of said securing means or its position or angle of attachment, that is to say, the securing or fastening means should be universal and standard to simplify manufacture and assembly. In the drawings I have shown three modifications of the same retainer. As shown, the same is formed of a strip of metal bent to provide a front guard 7, two side guards 8-8 and two attaching ears 9-9. In Fig. 1 only one side and one ear is visible, but in Figs. 2 and 3 the two sides and ears are seen. 10-10 represent pin, rivet or screw fastenings by which the holding ears 9 may be secured to the body 1 of the holder. When the holder is viewed from the side it will be seen that the retainer is fixed at an unvarying incline with reference to the adjacent portion of the commutator 3 so as to bring the forward part of the retainer relatively close to the commutator. It will also be observed that the lower edge of the strip forming the front part of the retainer is cut back somewhat to provide clearance, this cut-back portion extending not only across the lower edge of the front guard 7 but also partially across the adjacent lower edges of the sides 8-8. Manifestly, if the thickness of the brush 4 is greater than that indicated in Fig. 1, those portions of the strip at the front would be still further offset from the face 5 and would therefore have to be cut back still more, as shown in Fig. 2, wherein 7^a represents the front guard. Thus, as the degree of offset of the front portion of the retainer increases, the lower edge should be cut back still more to provide the adequate clearance. Three steps are shown in the drawings. For example, in Fig. 2 it will be observed that the retainer there shown is adapted to take a brush somewhat thicker than the brush 4 shown in Fig. 1, and accordingly the lower front portion, indicated at 7^a, is cut back more than shown in Fig. 1. In Fig. 3 the retainer is adapted to take a brush of still greater thickness, and here again it will be seen that the lower edge is cut back still more, the front guard being indicated at 7^b.

Attention is also directed to the notched upper part of the front guard shown in Figs. 1 and 2. This notch in Fig. 1 is indicated at 11, and in Fig. 2 at 11^a. By providing this notch, clearance is afforded for the end of the follower 6 when the brush has been worn down to a point where the follower end passes the upper edge of the retainer. Again, this notch renders somewhat more accessible for removal any remaining short portion of the brush that may stand in the retainer after the said brush has been worn down to the limit of its 110

usefulness. While it is desirable to have the notches 11 present in retainers adapted to the thinner brushes, it need not be present in all cases and need never be present in 5 retainers adapted to take the thickest brushes, as shown in Fig. 3.

While I have shown only three sizes herein, it will be understood that as many sizes may be made as required for the various 10 sizes of brushes. In all instances it will be observed the retainers are secured to the body of the brush holder in a predetermined position. Therefore, it requires no modification of the brush holder itself to apply 15 thereto retainers of any size. It will be understood that the width of the retainers may be varied at will in accordance with 20 brushes of different widths, but this will not affect either the positioning of the retainer on the holder nor the other features hereinbefore described. It will be observed that the degree to which the lower edge of the 25 strip is cut away increases with the degree of offset of the front guard from the brush supporting face of the holder itself, and it will also be observed that whenever the 30 lower edge of the front guard is cut away to provide clearance, the adjacent portions of the side guards 8-8 should also be correspondingly cut away for the same purpose.

In some instances the front guard bar could be entirely cut away at the middle, as indicated between the dotted lines shown in 35 Fig. 2, without departure from the spirit or scope of my invention.

What I claim is:

1. A brush retainer for brush holders comprising a front guard, two side guards, 40 the latter being extended to form ears for predetermined fixed engagement with the body of the brush holder, the lower edge of said retainer adjacent the front guard and the adjacent edges of the side guards being 45 partially cut away to afford clearance for a commutator, the extent to which said parts are cut away being in proportion to the degree of offset of the front guard from the brush supporting face of the holder.

2. A brush retainer for brush holders 50 comprising a front guard, two side guards, the latter being extended to form ears for predetermined fixed engagement with the body of the brush holder, the lower edge of said retainer adjacent the front guard 55 and the adjacent edges of the side guards being partially cut away to afford clearance for a commutator, the extent to which said parts are cut away being in proportion to the degree of offset of the front guard from 60 the brush supporting face of the holder, the upper edge of said strip adjacent the front guard being also cut away to afford clearance.

3. The combination of a brush holder comprising a body having a brush supporting face, a sheet metal brush retainer bent to form a front guard and two side guards, the latter being extended to form fastening ears, with means for securing said ears in a 70 predetermined fixed position on the body of the holder, said front guard being arranged in front of, and spaced away from, said brush supporting face, the middle portion of said strip being cut back at the lower 75 edge to provide clearance for a commutator under the outer end of said retainer, the amount to which said strip is cut back being in substantial proportion to the degree to which the front guard is offset from said 80 face.

4. In a brush holder having a brush supporting face arranged at an angle relatively to the commutating surface of a commutator, a sheet metal brush retainer carried by said holder and shaped to form a front guard spaced away from said supporting surface, and side guards connecting the same to said holder at opposite sides thereof, the lower edge of the front guard 90 being cut back to provide clearance for the commutator, the degree to which said bar is cut back being in substantial proportion to the degree of offset of the front guard from the brush supporting face of the 95 holder.

ROBERT N. BAYLIS.
